ALKYLATION OF AROMATIC HYDRO-CARBONS

Herman S. Bloch, Chicago, Ill., assignor to Universal Oil Products Company, Chicago, Ill., a corporation of Delaware

No Drawing. Application March 26, 1942,
Serial No. 436,314

10 Claims. (Cl. 260—671)

1

This is a continuation-in-part of my co-pending application Serial No. 398,194, filed June 16, 1941.

This invention is concerned with the interaction of aromatic hydrocarbons with olefins in the presence of a catalyst. It is more specifically concerned with a simple and easily regulated process involving the use of a catalyst which is altered only slightly in the course of the reaction but which catalyzes the desired conversion with a high degree of efficiency.

Processes for the formation of more highly alkylated aromatic hydrocarbons from less highly alkylated aromatic hydrocarbons are of importance not only from the standpoint of producing high antiknock motor fuel fractions but for preparing alkylated aromatic hydrocarbons useful as intermediates in the production of synthetic organic chemicals.

In one specific embodiment the present invention comprises a process for alkylating aromatic hydrocarbons with olefinic hydrocarbons in the presence of a hydrogen halide and of a molten mixture of metal halides of the Friedel-Crafts type.

Aromatic hydrocarbons, such as benzene, toluene, other alkylated benzenes, naphthalene, alkylated naphthalenes, other poly-nuclear aromatics, etc., which are alkylated by olefinic hydrocarbons as hereinafter set forth, may be obtained by the distillation of coal, by the dehydrogenation of naphthenic hydrocarbons, by the dehydrogenation and/or cyclization of aliphatic hydrocarbons, alkylated aromatic hydrocarbons, and alkylated naphthenic hydrocarbons, and by other means.

The olefins utilized for alkylating the aromatic hydrocarbons may be either normally gaseous or normally liquid. Typical gaseous olefins comprise ethylene, propene, and the butenes, while normally liquid olefins may consist of pentenes, hexenes, and higher boiling olefins. Olefinic hydrocarbons suitable for use in alkylation of benzene and its homologs and polynuclear aromatic hydrocarbons may be obtained from gaseous and liquid products formed from the cracking of hydrocarbon oils, by dehydrogenation of paraffins in the presence of catalysts, by the dehydration of alcohols, or from any other source.

The catalyst employed in the process of the present invention comprises molten mixtures of metal halides of the Friedel-Crafts type. These mixtures of metal halides have relatively low melting points and may comprise eutectic mixtures having minimum melting points in case such mixtures have fusion points corresponding to optimum temperatures for the alkylation reaction, but the usable catalysts are not limited merely to these eutectic mixtures.

Catalysts of the Friedel-Crafts type utilizable

2

in producing molten metal halide mixtures employed in the process of the present invention include the halides and particularly the chlorides and bromides, of such metals as aluminum, zirconium, zinc, tin, antimony, boron, cadmium, chromium, iron, etc., although it is recognized that they are not interchangeable in any given type of reaction and that not all will catalyze certain alkylation reactions. Of the metal halides mentioned, aluminum chloride is generally the most applicable and zirconium chloride and zinc chloride follow in approximate order of decreasing activity. The low melting point mixtures, which are preferably used in accordance with the present invention, may include combinations of any of the known catalysts of the Friedel-Crafts type which have definite activity as catalysts for the alkylation of aromatic hydrocarbons. It may also be desirable to composite proportioned amounts of two Friedel-Crafts type catalysts with another metal salt of lesser catalytic activity to form a mixture with a relatively low solidification point. Preferred molten catalysts include a mixture of aluminum chloride and zinc chloride and also a 3-component catalyst comprising essentially a molten mixture of the chlorides of aluminum, zinc, and sodium.

The term solidification point is used in reference to that temperature at which complete solidification of the salt mixture occurs and in most cases the temperature of solidification is lower than the reaction temperatures found to give good results in the alkylation of an aromatic hydrocarbon by an olefin in the presence of the particular metal halide mixture employed. In this specification and in the claims the term molten mixture of metal halides is used in referring to a mixture of metal halides containing a substantial proportion of a Friedel-Crafts type catalyst and employed at temperatures above the solidification points of said mixtures.

Alkylation operations may be conducted by passing the aromatic and olefinic hydrocarbons upwardly through stationary pools of a molten catalyst salt mixture or by similarly passing the hydrocarbons upwardly countercurrent to a descending molten salt mixture in a substantially vertical reactor which may or may not contain filling or spacing materials such as crushed fragments of relatively inert packing material as for example silica, or which may contain regularly spaced pans or trays. Alkylation treatment may also be carried out by passing liquid or liquefied hydrocarbons and a proportioned amount of molten salt mixture through tubular elements preferably under conditions of turbulent flow, after which the products from the tubular reactors are discharged into separating chambers from which the hydrocarbon products are directed to fractionation and the separated salt mix-

ture is returned to further service as catalyst for effecting the alkylation of an additional quantity of an aromatic hydrocarbon by an olefinic hydrocarbon.

The conditions of temperature, pressure, and rate of flow which are utilizable for carrying out the desired alkylation reaction will vary with the compounds undergoing treatment and with the nature and composition of the catalyst used, and accordingly only relatively broad ranges can be given. In general suitable alkylation temperatures are above the solidification point of the catalyst mixture but below about 150° C. The operating pressure may vary from substantially atmospheric to approximately 100 atmospheres or more. Flow rates will obviously vary with the particular type of operation employed as well as with the characteristics of the charging stock. In order to favor the production of mono-alkylated aromatic hydrocarbons and to substantially avoid olefin polymerization, it is advisable to charge from about 1 to about 20 molecular proportions of aromatic hydrocarbon per 1 molecular proportion of olefinic hydrocarbon introduced to the alkylation reaction. It is preferable, however, to maintain a substantial molar excess of aromatic hydrocarbon to olefinic hydrocarbon throughout the entire reaction.

It is often desirable to have small but definite amounts of a hydrogen halide as hydrogen chloride or hydrogen bromide present in a reaction zone so as to promote the catalytic activity of the molten metal halide catalyst. The presence of hydrogen is advantageous in minimizing undesirable side reactions leading to the formation of relatively high molecular weight compounds.

The following example is introduced as characteristic of the practical operation of the process, although it is not presented with the intention of limiting the scope of the invention in exact correspondence with the numerical data presented.

80 parts by weight of benzene, 21 parts by weight of propene, and 8.2 parts by weight of a catalyst consisting of 65% by weight of aluminum chloride and 35% by weight of zinc chloride having a solidification point of 117° C. were placed in an autoclave and heated with stirring at 125° C. for 1.5 hours. The liquid hydrocarbon product, after separation from the catalyst, was washed, dried and distilled to separate unconverted benzene from alkylated benzene. The 89.2 parts by weight of washed and dried reaction product obtained was thus separated into the following fractions represented in terms of the weight per cent based upon the benzene charged and also upon the propene charged. It is noted that mono-isopropyl benzene was the major product.

Table

Fraction	Boiling Range, °C.	Weight Per Cent of Charged	
		Benzene	Propene
Gas		0	0
Benzene	75-85	57	
Intermediate	85-145	4.4	16.7
Monoisopropylbenzene	145-170	33.6	128
Intermediate	170-200	3.3	12.4
Di-isopropylbenzenes	200-204	3.5	13.3
Higher boiling products	Above 204	3.0	11.3
Distillation and Handling Loss		7.0	26.6

The bromine number of the entire hydrocarbon product was 1, thus indicating that substantially no propene polymers were present and that nearly all of the propene had been utilized to form alkylated benzenes. In spite of the rather large mechanical loss which amounted to about 15 parts by weight of the total 101 parts by weight of benzene and propene charged, the alkylated benzenes recovered represented approximately 180% of the propene charged. Of the alkylated benzenes formed and recovered, approximately 75% by weight was mono-isopropylbenzene.

The character of the invention and the type of results obtained by its use in practice are evident from the preceding specification and example given, although they are not to be considered as imposing undue limitations upon its generally broad scope.

I claim as my invention:

1. An alkylation process which comprises reacting an aromatic hydrocarbon with an olefinic hydrocarbon at an alkylation temperature below about 150° C. in the presence of a catalyst comprising a mixture of a major mol proportion of an aluminum halide and a minor mol proportion of a zinc halide, said halides being so proportioned that the mixture thereof is in molten condition at said alkylation temperature.
2. The process of claim 1 further characterized in that said aromatic hydrocarbon comprises a mono-nuclear aromatic hydrocarbon.
3. The process of claim 1 further characterized in that said aromatic hydrocarbon comprises benzene.
4. The process of claim 1 further characterized in that said aromatic hydrocarbon comprises a polynuclear aromatic hydrocarbon.
5. The process of claim 1 further characterized in that said olefinic hydrocarbon comprises a normally gaseous olefin.
6. The process of claim 1 further characterized in that said olefinic hydrocarbon comprises propylene.
7. An alkylation process which comprises reacting an aromatic hydrocarbon with an olefinic hydrocarbon at an alkylation temperature below about 150° C. in the presence of a catalyst comprising a mixture of a major mol proportion of aluminum chloride and a minor mol proportion of zinc chloride, said chlorides being so proportioned that the mixture thereof is in molten condition at said alkylation temperature.
8. The process of claim 7 further characterized in that said catalyst also contains sodium chloride.
9. An alkylation process which comprises reacting an aromatic hydrocarbon with an olefinic hydrocarbon at an alkylation temperature below about 150° C. in the presence of a catalyst comprising a mixture of aluminum chloride and zinc chloride in the ratio of about 2 mols of aluminum chloride per mol of zinc chloride, said mixture being in a molten condition at said alkylation temperature.
10. An alkylation process which comprises reacting benzene with propylene at an alkylation temperature below about 150° C. in the presence of a catalyst comprising a mixture of aluminum chloride and zinc chloride in the ratio of about 2 mols of aluminum chloride per mol of zinc chloride, said mixture being in a molten condition at said alkylation temperature.
